GRID FOR COOKING RANGE

Clifford E. Hammel, Belleville, Ill., assignor to Peerless Enamel Products Co., Belleville, Ill., a corporation of Illinois

Filed Oct. 18, 1968, Ser. No. 14,064

Term of patent 14 years

Int. Cl. D7—04

U.S. Cl. D81—25

FIG. 1

FIG. 1 is a top plan view of a grid for a cooking range, showing my new design:

FIG. 2 is a cross section taken on line 2—2 of FIG. 1, and

FIG. 3 is a bottom plan view thereof.

I claim:

The design for a grid for cooking range, substantially as shown.
